US00D989376S

(12) **United States Design Patent** (10) **Patent No.:** **US D989,376 S**
(45) **Date of Patent:** **** Jun. 13, 2023**

(54) **CULTIVATION LIGHT**

(71) Applicants: **Brandon Burkhart**, Mira Loma, CA
(US); **Thomas O'Connor**, Mira Loma, CA (US)

(72) Inventors: **Brandon Burkhart**, Mira Loma, CA
(US); **Thomas O'Connor**, Mira Loma, CA (US)

(73) Assignee: **HGCI, Inc.**, Las Vegas, NV (US)

(**) Term: **15 Years**

(21) Appl. No.: **29/834,656**

(22) Filed: **Apr. 13, 2022**

Related U.S. Application Data

(63) Continuation of application No. 29/732,193, filed on Apr. 22, 2020, now Pat. No. Des. 949,454.

CLAIM

We claim the ornamental design for a cultivation light, as shown and described.

DESCRIPTION

FIG. 1 is a top, front isometric view of a cultivation light, showing our new design.

FIG. 2 is a front elevation view thereof.

FIG. 3 is a rear elevation view thereof.

FIG. 4 is an enlarged left side elevation view thereof.

FIG. 5 is an enlarged right side elevation view thereof.

FIG. 6 is a top plan view thereof; and,

(Continued)

FIG. 7 is a bottom plan view thereof.
The broken lines illustrate unclaimed portions of the cultivation light that form no part of the claimed design.

1 Claim, 5 Drawing Sheets
